ICE SKATE AND ICE SKATE SHOE PRO-
TECTOR

Michael Goldenberg, Philadelphia, Pa.

Application April 7, 1931. Serial No. 528,317

9 Claims. (Cl. 208—183)

This invention relates to ice skates and ice skate shoes and has for its object the provision of means carried by either the ice skate or the ice skate shoe which will protect the ice skate shoe and especially the sides thereof from wear.

The above as well as other objects of this invention and the advantages arising therefrom will become more evident from the following specification and the drawings which form a part 10 thereof.

In the drawings Figure 1 is a bottom view of my novel skate and shoe combination wherein the shoe protector is formed as an integral part of the skate. Portions of the skate are shown 15 broken away for the purpose of more clearly illustrating its structure.

Figure 2 is a side view of the disclosure shown in Figure 1, a portion of the shoe being torn away.

Figure 3 is a bottom view of my novel skate and shoe combination wherein the shoe protector is made of units independent of the skate. A portion of each protector element is shown 20 broken away for the purpose of more clearly 25 illustrating their structure.

Figure 4 is a section taken along the line 4—4 of Figure 3.

Figure 5 is a perspective view of a modified 30 protector element of the type shown in Figures 3 and 4.

Figure 6 is a bottom view of my novel skate and shoe combination wherein the shoe protector is independent of the skate and wherein the shoe 35 protector elements are formed as an integral unit. Portions of the protector units are shown broken away for the purpose of more clearly 40 illustrating its structure.

Figure 7 is a view taken along the line 7—7 of Figure 6.

Figure 8 is a perspective of a modified unit of 45 the type shown in Figures 6 and 7.

Referring more particularly to the drawings 50 wherein similar reference numerals denote similar parts, reference numeral 1 denotes a skating shoe of the well known type adapted to have an ice skate attached thereto. The shoe 1 has the usual sole member 2 and the upper member 3. (The shoe in and of itself does not form a part of my invention and since it is well known in the art will not be further described here.)

Referring more particularly to the disclosure 55 of Figures 1 and 2, reference numeral 4 denotes a skate which has its heel plate 6 and ball plate 7 attached to the sole 2 of the shoe 1 by means of rivets 9. The skate 4 is composed of main tubu-

lar standards 5 and a front brace 10 which support the bearing element 32. The tubular members 5 are held in place by the heel and ball plates 6 and 7 respectively. The front brace 10 is attached to the ball plate 7 and the shoe 1 at 60 the points 11. With the exception of the novel structure of the ball plate 7 which will be hereinafter more particularly described, the skate 4 is of the well known type adapted to be attached directly to a shoe. The ball plate 7 terminates 65 at its outer ends in downwardly extending protecting flanges 8 which are close to and follow the contour of the sole member 2 to which they are contiguous. These protecting flanges serve to protect the portion of the shoe which they 70 cover from wear.

Referring more particularly to Figures 3 and 4, reference numeral 4' denotes a skate which differs from that shown in Figures 1 and 2 only in the fact that the ball plate does not have 75 downwardly extending flanges formed integral therewith. Instead, the skate 4' has the ball plate 12 found in the skates which are adapted for direct attachment to the shoe. (Skates of this type are well known in the art and for that reason will not be more particularly described here.) Attached to sole 2 of the shoe 1 by means of the rivets 9 which connect the ball plate 12 to the said sole 2 are a pair of protecting elements 13. Each element 13 has a 80 horizontal lower shoe attaching flange 14 which terminates in a downwardly extending protecting flange 15.

The shoe protecting element 16 shown in Figure 5 is similar in structure and function to the protecting element shown in Figures 3 and 4. The protecting flange 17 of the element 16 is exactly similar to the protecting flange 15 of the element 13. The attaching flange 18 of the element 16 is similar in function to the attaching flange 14 of the element 13 and differs from the attaching flange 14 in structure only in the fact that the attaching flange 18 is provided with a plurality of indented or cut out members 19 which function to cut down the weight of the protecting element. Both the attaching flanges 18 and 14 are provided with suitable holes such as 20 (see Figure 5) through which the attaching rivets 9 may extend.

Referring more particularly to Figures 6 and 7, reference numeral 4' denotes a skate exactly similar to that shown in Figures 3 and 4. Instead of using a shoe protecting unit composed of the independent protecting elements there is provided a shoe protecting unit wherein the pro-

ector elements are combined in an integral construction. The shoe protecting unit 21 shown in Figures 6 and 7 is composed of two protecting elements 33 joined together by the corrugated plate 24. The corrugated plate permits the adjustment of the unit 21 on shoes of differing toe and sole width. Each element 33 has an attaching portion 22 and a protecting flange at right angles thereto as shown. The attaching flanges 22 are attached to the sole 2 of the shoe 1 by the rivets 9 which extend through suitable apertures in the attaching flanges 22 and which also serve to attach the ball plate 12 of the skate 4' to the sole 2 of the shoe 1.

15 The shoe protecting unit 26 shown in Figure 8 is similar in structure and function to the protecting unit 21 shown in Figures 6 and 7. The protecting flange 27 of the unit 26 being exactly similar to the protecting unit 23 of the unit 21 and the corrugated connecting plate 29 of the unit 27 being exactly similar to the connecting plate 24 of the unit 21. The attaching flange 28 of the unit 27 is similar in function to the attaching portion 22 of the unit 1, and differs therefrom in structure only because of the fact that the attaching portion 28 is provided with a plurality of cut-out or indented portions 30 which serve to lighten the unit 1. Both the attaching flange 28 and the attaching flange 22 are provided with a plurality of holes such as 34 in Figure 8 through which the attaching rivets may extend.

35 The above disclosure is to be understood as being by the way of illustration only and not by the way of limitation since many changes may be made in the disclosure shown without departing from the spirit of my invention. For instance, instead of making the protector plates out of sheet steel or aluminum, some other metal or material having the desirable qualities of strength combined with lightness may be used. Or the protector elements, when made independent of the ball plate of the skate, may be attached at some point on the sole independent of attaching point 40 of the ball plate. Or the protector elements may be made in a single plate. These as well as many other changes are contemplated by me and for that reason it is my desire that the claims which are hereunto appended for the purpose of defining my invention be limited only by the prior art.

50 Having described my invention what I claim as new and useful is:

1. An article of manufacture consisting of a shoe; a skate member having a heel and ball portion, each fixedly attached to the sole of the said shoe; and upwardly extending shoe protecting flanges fixedly attached to at least one of the said elements at the point of attachment of and by the same attaching means which attach the said ball portion of the said skate to the said sole of the said shoe.
2. An article of manufacture consisting of a shoe; a skate member having a heel and ball portion each attached to the sole of the said shoe;

5 upwardly extending shoe protecting flanges fixedly attached to the said skate at the point of attachment of and by the same attaching means which attach the said ball portion of the said skate to the said sole of the said shoe; and a plate having indentations formed therein joining together the said upwardly extending flanges.

6 3. An article of manufacture consisting of a shoe; a skate member having a heel and ball portion each attached to the sole of the said shoe; upwardly extending shoe protecting flanges fixedly attached to the said skate at the point of attachment of and by the same attaching means which attach the said ball portion of the said skate to the said sole of the said shoe; and an upwardly extending plate having vertical corrugations formed therein joining together the said upwardly extending flanges.

7 4. In a skate,—adapted for direct attachment to a shoe and comprising a shoe attaching member consisting of a ball attaching member and a heel attaching member, and a bearing member carried by the said ball and heel attaching members,—means for protecting the shoe to which the said skate is to be attached, the said means consisting of an upwardly extending flange formed on the said ball member.

8 5. As an article of manufacture a skate adapted for direct attachment to a shoe, the said skate comprising a shoe attaching member consisting of a ball attaching member and a heel attaching member, a bearing member carried by the said ball and heel attaching members, and upwardly extending flanges carried by the said ball attaching member.

9 6. As an article of manufacture a protecting unit for skate shoes, the said protecting unit consisting of two protecting elements joined together, each said protecting element consisting of an attaching flange and an upwardly extending shoe protecting flange.

10 7. As an article of manufacture a protecting unit for skate shoes, the said protecting unit consisting of two protecting elements joined together at their front ends by an upwardly extending plate having vertical indentations formed therein; each of the said protecting units consisting of an attaching flange and an upwardly extending shoe protecting flange.

11 8. An article of manufacture consisting of a shoe; a skate member having a heel and ball portion fixedly attached to the sole of said shoe; and upwardly extending shoe protecting flanges attached to and carried by the ball portion of said skate.

12 9. An article of manufacture consisting of a shoe; a skate having a heel and ball portion fixedly attached to the sole of said shoe; upwardly extending shoe protecting flanges fixedly attached to one of the said members; and a plate having indentations formed therein joining together the said upwardly extending flanges.

MICHAEL GOLDENBERG.
